UNITED STATES PATENT OFFICE

154,248

DESIGN FOR A CIGARETTE PACKAGE RACK

Neal E. Durbin, Seattle, Wash.

Application January 10, 1948, Serial No. 143,658

Term of patent 14 years

(Cl. D85—2)

To all whom it may concern:

Be it known that Neal E. Durbin, a citizen of the United States, residing at Seattle, Washington, has invented a new, original, and ornamental Design for a Cigarette Package Rack, of which the following is a specification, reference being had to the accompanying drawing, forming a part thereof, in which

Fig. 1 is a perspective view of a cigarette package rack, showing my new design;

Fig. 2 is a side elevational view of the rack shown in Fig. 1; and

Fig. 3 is a vertical sectional view taken on the line 3—3 of Fig. 1.

Fig. 4 is a view in rear elevation in the plane of line 4—4 of Fig. 2.

The dominant features of my design reside in those portions shown in full lines.

I claim:

The ornamental design for a cigarette package rack, as shown, and described.

NEAL E. DURBIN.
